UNITED STATES PATENT OFFICE.

FRANZ RUDOLF LORENZ, OF GUMBINNEN, GERMANY.

FEEDING AND IGNITING MECHANISM FOR EXPLOSION-MOTORS.

No. 819,148.

Specification of Letters Patent.

Patented May 1, 1906.

Application filed November 28, 1904. Serial No. 234,569.

To all whom it may concern:

Be it known that I, FRANZ RUDOLF LORENZ, a subject of the German Emperor, and a resident of Gumbinnen, Germany, have invented a certain new and useful Feeding and Igniting Mechanism for Explosive-Motors, of which the following is a specification.

The object of my invention is to provide an improved mechanism applicable to explosive-motors whereby solid explosives in the form of powder, cord, paste, gelatin, or the like are fed to the place of ignition in charges corresponding in amount to the power required to be developed by the motor.

Referring to the drawings, which form a part of this specification, Figure 1 is a horizontal section of the improved mechanism applied to a motor-cylinder of which only the rear end is shown. Fig. 2 is an elevation 15 of a detail drawn to a smaller scale. Fig. 3 is a cross-section on the line X X. Fig. 4 is a cross-section on the line Y Y, and Fig. 5 is a cross-section on the line Z Z, of Fig. 1. Figs. 6 and 7 are respectively a side elevation and a 20 front elevation of an enlarged detail.

A is the motor-cylinder, and A' is the explosion-chamber.

b is a feed-disk formed in its flat side with a number of perforations b', spaced equally 30 apart in a circle concentric with the center of the disk. The disk b is fixed on a shaft d, which is rotatably supported at its front end in the end of the motor-cylinder and at its rear end in a cross-piece W, forming 35 part of the framing of the apparatus, which comprises the cross-piece D and the stay-bars r r h. The disk b is adapted to be rotated on its axis, so as to bring at each working stroke of the motor one of its perforations b' in front of the delivery end of a 40 worm conveyer C C', hereinafter referred to, while another of the perforations b' is brought into coincidence with the inlet-orifice of the explosion-chamber A', all the perforations b' 45 coming thus successively in operation.

The mechanism for rotating the feeding-disk b consists of a disk f, formed on its front face with ratchet-teeth f' and on its edge with ratchet-teeth f''. A disk e is loose on the shaft d in front of the disk f. It is provided on part of its edge with teeth e' and on its face with teeth e'', engaging with the teeth of the disk f.

g is a lever rocking on the axle h. At one 55 end it is formed as a circular rack, gearing with the teeth e', and its other forked end

carries an antifriction-roller g', adapted to be actuated by a cam g², formed on the collar g³ of a shaft T. At every revolution of the motor the lever g is caused by the cam g³ to rotate the disk e forward, during which movement a spring 8 on the shaft d forces the toothed disk e into engagement with the teeth of the disk f, whereby the disk f is also caused to rotate forwardly and through the 60 shaft d to rotate the feed-disk b forward to the extent required to bring fresh perforations b' into position. A spring 9 returns the lever g into its initial position, which is determined by a stop v. During this return 65 movement a pawl 4 engages with the outer ratchet-teeth of the disk f, and thus prevents the latter from rotating. C² is a hopper containing the explosive communicating with the casing c of a worm conveyer C', which 70 delivers the explosive into the perforation b' of the feed-disk b that happens to be coincident with the delivery-orifice of the conveyer.

In order to prevent the gases generated in the explosion-chamber A' from escaping 75 back through the narrow space normally existent between the front of the feed-disk b and the rear of the motor-cylinder, means are provided whereby shortly before each explosion the disk b between its intermittent 80 rotary movements is forced in the direction of its axis tightly against the wall of the motor-cylinder. This intermittent axial movement is effected by means of a screw-spindle l, which is mounted behind the disk b in the 85 axis of the explosion-chamber A' and works in a nut that is held by a cross-piece q, fixed to the stay-bars r r.

n is a lever rocking on the axle h. It is formed at one end as a circular rack n', engaging 90 with teeth l', formed on the screw-spindle l, and provided at its other end with an antifriction-roller n², adapted to be actuated by a cam n³, formed on the collar n⁴ of the shaft T. At the proper time the cam n³ 95 operates the lever n to rotate the screw-spindle l, so as to force the feed-disk b tightly against the motor-cylinder. After the explosion the screw l is moved back away from the motor-cylinder by a spring 7, or vice 100 versa. By a suitable arrangement of the parts the screw-spindle l may be moved up against the motor-cylinder by the spring 7 and be moved back by the cam n³.

1 is a link connecting the lever n with a 110 lever 2, which rocks at one end on a center 3 and is situated between the feed-disk b and

- the conveyer *c*. The lever *2* is wedge-shaped at its middle, where it is formed with a hole which coincides with the delivery-orifice of the conveyer *c* and with a perforation *b'* of the feed-disk *b* during the stoppage of the disk *b* between its intermittent rotary movements. During the said stoppage the conveyer *c* forces the explosive out at its delivery end through the hole in the lever *2* into the coincident perforation *b'* of the feed-disk *b*. Then as the lever *2* is rocked on its center *3* by the lever *n* the sharpened edge of its hole separates the charge of explosive contained in the perforation *b'* from the main body contained in the conveyer. The space between the conveyer delivery-orifice and the feed-disk *b* is completely filled up by the lever *2*, so that no loss of explosive can take place. The feed of the explosive is regulated automatically by means of the conveyer *C* in combination with the following mechanism: The axle of the conveyer is prolonged as a square shaft *t*, on which a disk *t'* can be slid to and fro by means of a forked piece *t''*, that is slid to and fro, but cannot rotate, on a square bar *t''*, fixed at its ends in the cross-pieces *W D*, by means of a lever *t''*, pivoted at *t''* and operated from the sleeve *t'* of a centrifugal governor *t''*.
- u'* is a drum capable of sliding along a square shaft *u''*, Fig. 2, while rotating therewith. It is formed with a longitudinal cam-like prominence *u''*, tapering toward its rear end. The shaft *u''* is rotated by means of pulleys *t''* from the shaft *T*. As the drum *u'* rotates its cam *u''* causes the disk *t'* to rotate intermittently, so that at each revolution of the drum *u'* the conveyer-worm *C'* is caused to feed a quantity of explosive forward. The extent of this rotation, and consequently the forward feed of the explosive, is regulated by the governor *t''*, which shifts the forked piece *t''*, and with it the disk *t'*, along the cam *u''*. For the purpose of insuring driving contact between the disk *t'* and the cam *u''* the drum-shaft may be carried in movable bearings pressed by strong springs toward the disk *t'*.
- The means for regulating at will the quantity of explosive to be fed to the motor, whereby the speed of the motor can be increased or reduced, comprise a frame *u*, which has extensions *u'*, working on a screw-spindle *u''*, and has also arms *u''*, that engage, by means of studs *u''*, in grooved collars *u''*, arranged one at each end of the cam-drum *u'*. By rotating the screw-spindle *u''* in one or the other direction the drum *u'* can be shifted along its shaft so as to bring a larger or a smaller radius of the cam *u''* in contact with the disk *t'*, thereby increasing or diminishing the speed of rotation of the latter, and consequently, also, of the conveyer-worm *C'*, which thus delivers a greater or small quantity of charge.
- u''* are preferably made springy in

order to soften the impact between the disk *t'* and the cam *u''*.

The means for igniting or exploding the explosive charge contained in the perforation *b'* of the feed-disk *b* opposite the explosion-chamber *A'* are as follows: *a* is a chain strip of detonators spaced uniformly apart and provided with driving-holes *a'*. *a''* is an anvil-plate which is situated between the feed-plate perforation *b'* and the screw-spindle *l*. It has a slot *a''* and a firing-hole *a''*, Figs. 6, and 7, through which the spark passes to the charge in the disk *b*. The anvil-plate *a''* is mounted on studs on which it can be slid close up to the feed-disk *b*, so as to make a gas-tight joint therewith by the forward movement of the screw-spindle *l*. Springs *a''* are provided to move back the anvil-plate away from the feed-disk *b* when the forward pressure of the screw-spindle *l* has ceased in order to prevent any hindrance to the rotation of the feed-disk. The strip of detonators *a* is caused to move intermittently through the slot *a''* in the anvil-plate *a''*, so as to bring the detonators successively opposite the firing-hole *a''* by means of guides *w''* and peg-rollers *w''*, which are mounted on shafts *w* and engage in the holes *a'* of the strip, Fig. 3. The requisite intermittent rotary motion is imparted to the shafts *w* by means of a ratchet-wheel *w''* and pawl *w''*, operated by the lever *n*. The detonator-strip *a* is first threaded by hand vertically upward between the peg-roller *w''* (not shown) on the left-hand end of the horizontal shaft *w*, Fig. 3, and its guide *w''*, then with a rounded right-angled turn horizontally through the slot *a''* in the anvil-plate *a''*, and then with a second rounded right-angled turn vertically down between the peg-roller *w''* on the right-hand end of the horizontal shaft *w* and its guide *w''*. The peg-rollers and their guides are exactly the same on both ends of the shaft *w*. Suitable rollers *x* may be provided for giving the strip its turning movement. When the left-hand portion of the lever *n* rises, its attached pawl *w''* operates the ratchet-wheel *w''* to rotate the horizontal shaft *w* in such a manner as to cause the strip *a* to be fed upward by the left-hand-roller and downward by the right-hand roller, as indicated by the arrows in Fig. 3. The strip *a* is drawn through the slot *a''* in the anvil-plate *a''* by means of the right-hand peg-roller *w''* on the vertical shaft *w*, which is driven by bevel-wheels from the horizontal shaft *w*.

The detonators are detonated by means of a firing-pin *s*, Fig. 1, which extends longitudinally through the screw-spindle *l* and is impelled by the spring *s'* to detonate the detonators at the proper moment. The firing-pin has a central enlarged portion having an inclined face *s''*, which fits normally against a similarly-inclined face on the screw-spindle *l*. When the screw-spindle is rotated in its

- rearward movement, the inclined face of the screw-spindle acting on the face s^2 forces back the firing-pin against the opposition of the spring s' , and thus cocks the firing-pin.
- 5 The firing-pin is locked in its cocked position by a lever s^3 , Fig. 5, which rocks on the axle h and one end of which is actuated by a cam s^4 on the shaft T , while its other end carries a locking-nose s^5 . A spring s^6 , attached to the 10 framing of the apparatus, acts on the lever s^3 in opposition to the cam s^4 . In its normal position the left-hand end of the lever, as shown, is situated just out of engagement with a stop s^7 , formed on the firing-pin s , while its right-hand end is in contact with the 15 smallest radius of the cam s^4 .
- The operation of the mechanism is as follows: From the continuously and uniformly rotating shaft T the square shaft u^3 and 20 through it the cam-drum u^6 u^7 are also rotated continuously and uniformly by means of the driving-gear t^9 . By the action of the cam-drum the disk t^2 is rotated intermittently, as are also by its means the square 25 shaft t and the screw conveyer c' , which delivers the explosive into that perforation b' of the now stationary feed-disk b which happens to be in front of its delivery-orifice. The quantity of the explosive so delivered by 30 the conveyer is regulated automatically by the centrifugal governor, which acts through the lever t^5 to shift the disk t^2 over a larger or small radius of the cam-drum u^6 u^7 , and thus cause the disk t^2 and through its means the 35 conveyer C' to rotate at a greater or less speed, and thereby deliver more or less explosive into the aforesaid perforation b' . Additional regulation may be effected at will by the attendant of the motor by rotating 40 the screw-spindle u^8 in one or the other direction, as desired, by means of a crank-handle. On the completion of the delivery by the conveyer the lever 2 is operated by the lever n to sever with the knife-edge of its 45 central orifice that portion of explosive contained in the aforesaid perforation b' and constituting a charge from the main mass still in the conveyer. Then the feed-disk b is rotated forward, by means of the lever g 50 and ratchet mechanism e e' e^2 f f' 4, to an extent sufficient to bring the following empty perforation b' opposite the delivery-orifice of the conveyer for the purpose of being charged with explosive, as just above described.
- 55 This partial rotation of the feed-disk b brings at the same time a charged perforation of the disk b in front of the explosion-chamber A' , when either the spring 7 or the lever n immediately operates the screw-spindle l to force 60 the disk b , with its loaded perforation b' , gas-tight against the orifice of the explosion-chamber. The charge in the said loaded perforation is then ignited by the lever s^8 lifting its locking-nose s^5 from the stop s^7 , and 65 thus releasing the cocked firing-pin s , which,

impelled by the spring s' , strikes with force through the slot a^3 of the anvil-plate a^2 and detonates one of the detonators of the detonator-strip a , the spark thus produced igniting through the firing-hole a^4 the charge in the 70 disk perforation b' . The explosion-gases sweep through the explosion-chamber A' into the cylinder A to produce the working stroke of the motor. When the explosion-gases have passed through the exhaust-valve out of the 75 motor-cylinder A , either the lever n or the spring 7 (or vice versa) rotates the screw-spindle l , so as to bring back the disk b away from its gas-tight contact with the motor-cylinder, and thus render the said disk free to make a 80 fresh forward partial rotation, as above described. The same movement of the lever n acts to feed a fresh detonator in front of the firing-hole a^4 in the anvil-plate a^2 through the medium of the driving-rollers w^6 , shafts w , 85 ratchet-wheel w^3 , and pawl w^2 . Also the same movement of the lever n serves also to depress the link 1, so as to bring the knife-edged hole in the cutting-lever 2 back in front of the delivery-orifice of the conveyer c . 90 The mechanism now recommences the hereinbefore-described cycle of operations for the next working stroke of the motor.

Having now described my invention, what I claim as new, and desire to secure by Letters Patent, is—

1. In an explosion-motor worked by solid explosive the combination with the motor-cylinder, of an axially-slidable feed-disk having equally-spaced perforations equidistant 100 from its axis, means for rotating the feed-disk intermittently so as to bring each perforation in turn in coincidence with the inlet-orifice of the explosion-chamber of the motor-cylinder, a screw conveyer for charging the perforations of the feed-disk in succession in the intervals between the partial revolutions of the feed-disk, means for rotating said conveyer intermittently, means for automatically regulating the speed of said conveyer, means for 105 optionally varying the speed of said conveyer, means for separating the charge of explosive in the perforations of the feed-disk from the mass in the conveyer, and for obturating the space between the feed-disk and 110 said conveyer, an anvil-plate having a firing-hole opening into each perforation of the feed-disk when the same is in coincidence with the said explosion-chamber, means for pressing the feed-disk into gas-tight contact 115 with the said explosion-chamber just before and during the explosion, means for feeding a chain of detonators intermittently through said anvil-plate, a firing-pin for exploding each detonator as it comes in coincidence 120 with the said firing-hole, and means for cocking and releasing said firing-pin, substantially as set forth.
2. In an explosion-motor worked by solid explosive the combination with the motor- 130

- 1 cylinder, of a feed-disk having equally-spaced perforations equidistant from its axis, mounted in an axially-slidable manner on a shaft, a disk keyed on said shaft having outer ratchet-teeth and inner ratchet-teeth, a pawl adapted to engage with said outer ratchet-teeth, a tooth-clutch loose on said shaft, having also gear-teeth, a spring tending to press said tooth-clutch into engagement with said inner ratchet-teeth, and a rocking lever bearing at one end on a cam on a revolving shaft and provided at its other end with a circular rack engaging with the gear-teeth of said toothed clutch, whereby the feed-disk is rotated at intervals through part of a revolution so as to bring an empty perforation in coincidence with the charging-orifice of the screw conveyer, and also a charged perforation in coincidence with the inlet-orifice of the explosion-chamber of the motor-cylinder, and whereby the feed-disk is caused to pause between said intervals for the purpose of charging the one perforation and exploding the charge in the other perforation, substantially as set forth.
2. In an explosion-motor worked by solid explosive, the combination with the motor-cylinder, of an axially-slidable intermittently-rotating feed-disk having equally-spaced perforations equidistant from its axis, a screw conveyer delivering explosive into the perforations of the said disk, and a lever of wedge-shaped cross-section for obturating the space between the delivery-outlet of the conveyer and the feed-disk between the intervals of charging the perforations in the feed-disk, said lever having a hole through which explosive is charged by the conveyer into the perforations in the feed-disk, and said hole being formed with a knife-edge whereby the charge contained in the perforation in the feed-disk is severed from the mass in the conveyer, with means for actuating said lever, substantially as set forth.
3. In an explosion-motor worked by solid explosive, the combination with the motor-cylinder, of an axially-slidable intermittently-rotating feed-disk having equally-spaced perforations equidistant from its axis, a screw conveyer delivering explosive into the perforations of the said disk, and a lever of wedge-shaped cross-section for obturating the space between the delivery-outlet of the conveyer and the feed-disk between the intervals of charging the perforations in the feed-disk, said lever having a hole through which explosive is charged by the conveyer into the perforations in the feed-disk, and said hole being formed with a knife-edge whereby the charge contained in the perforation in the feed-disk is severed from the mass in the conveyer, with means for actuating said lever, substantially as set forth.
4. In an explosion-motor worked by solid explosive, the combination with the explosion-chamber of the motor-cylinder, of an axially-slidable intermittently-rotating feed-disk having equally-spaced perforations equidistant from its axis, a screw-spindle parallel to the axis of the feed-disk, and axial with the inlet-orifice of the explosion-chamber of the motor-cylinder, and having gear-teeth, a nut prevented from motion in which said screw-spindle works, a spring tending to rotate said screw-spindle to force said feed-disk into gas-tight contact with the motor-cylinder just before and during the explosion, a rocking lever bearing at one end on a cam on a rotating shaft, and formed at its other end with a circular rack gearing with the teeth of the screw-spindle whereby the said rocking lever is actuated by said cam to revolve said screw-spindle so as to move away from said feed-disk after the explosion, substantially as set forth.
5. In an explosion-motor worked by solid explosive, the combination of an axially-slidable intermittently-rotating feed-disk having equally-spaced perforations equidistant from its axis, a screw conveyer for delivering explosive into the perforations of said feed-disk, a disk on the conveyer-shaft, and a continuously-revolving cam-drum in frictional contact with said disk, whereby said cam-drum acts upon the said disk so as to rotate the conveyer-shaft intermittently, substantially as set forth.
6. In an explosion-motor worked by solid explosive, the combination of a screw conveyer for delivering explosive, a square extension of the conveyer-shaft, a slidable disk on said square extension, a continuously-rotating cam-disk in frictional contact with said disk, a centrifugal governor and a part actuated by said centrifugal governor, whereby said slidable disk is moved automatically along the square extension-shaft by the centrifugal governor, so as to be rotated at speeds corresponding to the varying radius of the said cam-drum, substantially as set forth.
7. In an explosion-motor worked by solid explosive, the combination of a screw conveyer for delivering explosive, a disk on the conveyer-shaft, a continuously-rotating cam-drum slidable along a square shaft, a screw-spindle, nuts on said screw-spindle, arms carried by said nuts adapted to bear against each end of the said cam-drum, and a crank-handle for rotating said screw-spindle, whereby said screw-spindle may be optionally rotated so as to cause said cam-drum to slide along its shaft and bring its greater or less radius in contact with the said disk, and thus vary the speed of the conveyer, substantially as set forth.
8. In an explosion-motor worked by solid explosive the combination of an axially-slidable intermittently-rotating feed-disk having equally-spaced perforations equidistant from its axis, an anvil-plate having a transverse slot with a firing-hole axial with the inlet-orifice of the explosion-chamber of the motor-cylinder, situate behind said feed-disk, means for feeding a chain of detonators intermittently through said slot, and a firing-pin for detonating each detonator as it comes in coincidence with said firing-hole, substantially as set forth.
9. In an explosion-motor worked by solid explosive, the combination of an anvil-plate having a transverse slot with a firing-hole, a chain of detonators having driving-holes, and driving-pin rollers, whereby the detonator-chain is fed intermittently through the slot in the anvil-plate so as to bring each detonator in turn in coincidence with the said firing-hole, substantially as set forth.
10. In an explosion-motor worked by solid explosive, the combination of an intermittently-rotating screw-spindle having an axial

hole, and an inclined rear face, a firing-pin extending through the said hole in the screw-spindle, and having an enlarged portion formed with an inclined front face, a firing-
5 spring tending to impel said firing-pin forward, a stop on said firing-pin, a rocking lever bearing at one end on a cam on a continuously-revolving shaft, and provided at its other end with a catch adapted to engage with
10 the stop on the firing-pin, whereby when said screw-spindle rotates it forces back the firing-pin in opposition to the firing-spring and thus cocks the firing-pin, the firing-pin being then

retained in its cocked position by the catch on said rocking lever engaging with the stop 15 on the firing-pin, and whereby the firing-pin is released at the proper time by the action of the cam on the rocking lever, substantially as set forth.

In witness whereof I have hereunto set my 20 hand in presence of two witnesses.

FRANZ RUDOLF LORENZ.
